Des. 180,747
Patented Aug. 6, 1957

180,747

SLIDE FILE BOX OR SIMILAR ARTICLE

James H. Parcher, Hatboro, Pa.

Application October 23, 1956, Serial No. 43,469

Term of patent 14 years

(Cl. D61—1)

Fig. 1 is a perspective view showing the front, top and right side of a slide file box or similar article, embodying my new design;

Fig. 2 is a front elevational view;
 Fig. 3 is a right side elevational view;
 Fig. 4 is a top plan view;
 Fig. 5 is a rear view;
 Fig. 6 is a bottom plan view; and
 Fig. 7 is a perspective view of said box with the cover thereof in an open position.

I claim:

The ornamental design for a slide file box or similar article, as shown.
